RAZOR BLADE HOLDER

John W. Clark, Washington, D. C.

Application September 20, 1946, Serial No. 698,234

1 Claim. (Cl. 30—70)

1

This invention has to do with safety razors using blades of the wafer type.

The invention relates to a novel blade holding razor part, here shown as a razor cap, on which the blade engaging portions are formed. The cap construction here disclosed is adapted to novel form of blade disclosed, and has novel features which make the assembling of the blade and the razor part a simple and expeditious matter, the blade, when placed on the cap, sliding over curved or crowned surfaces on the razor part with which it is to be assembled in such fashion as to drop easily and automatically to its final position with a minimum of effort on the part of the user.

In the drawings herewith is illustrated a blade holder embodying my invention, and in said drawings:

Figure 1 is a plan view of a blade arranged to be associated with the improved holder.

Figure 2 is a view similar to Figure 1 showing the blade holding and centering rib in section; this view being substantially on the line 2—2, Figure 3.

Figure 3 is a view of a flexed blade with its cap and guard taken substantially on the line 3—3 of Figure 2.

Figure 4 is a view of a flexed blade with its cap and guard taken substantially on the line 4—4 of Figure 2.

Figure 5 is a view in plan of the cap.

Figure 6 is a sectional view of the cap on substantially the line 6—6 of Figure 5.

Figure 7 is an end view of the cap.

Figure 8 is a sectional view on substantially the line 8—8, Figure 6.

Figure 9 is a sectional view on substantially the line 9—9 of Figure 6.

In the description which follows the drawing will be referred to by numbers, and the same numbers will designate the same parts in the several views.

The blade 10 arranged to be carried by the holder may be provided with an elongated centrally disposed slot or opening 11 (Fig. 1) which terminates at its ends in transversely curved slots or lateral openings 12 equally distant from the side edges of the blade and struck out from the center as the curved ends of the blade so as to be substantially parallel therewith. Blade areas 13 are disposed on each side of the slots 12 and blade areas 14 are located at the ends of the slots 12.

The guard 15 and cap 16 which form the blade holding assemblage, are designed for the blade

2

10 and are fashioned in novel form as to ensure easy and accurate seating of the blade, which, when brought to its final position can be clamped and held in perfect relation to the razor parts and for shaving action.

5 The blade engaging rib 15 is here shown as formed on the cap 16. It is conceivable that it might be placed on the guard 16', as blade engaging members have been formed on either the cap or guard, and infrequently on both. The prevailing and better practice is to place such members on the cap, as here shown. It is to be understood, however, that no limitation as to forming blade engaging members on a particular 10 razor part is to be imposed because of this illustrative disclosure. As stated, the longitudinal rib section 15 is closely fitted to the longitudinal portion of the slot 11 in the blade so that side play of the blade is prevented. Rib 15 has a longitudinally curved crown 17 which extends throughout its entire length, this crown 17 sloping in opposite directions from the high point or maximum height 18 at the usual threaded guard attaching post 19. Rib 15 is also curved 15 laterally, as shown in Figs. 4, 6 and 8, so that a rib having a compound curved crown is provided. With the rib 15, formed with the curved crown as described, a blade, when dropped over the post 19, will rest on the peak of the crowned rib, and, 20 by reason of the longitudinal and lateral curves or inclines of the crown, can be moved readily to its final position for full engagement with the rib 15. The blade tends automatically to fall in its final position as it contacts the rib and is straightened out, this being due to the curvatures of the 25 rib crown.

The laterally extended cut outs 12 at the ends of the longitudinal opening 11 in blade 10, have 30 been described, and to take care of these cut outs 12 and ensure complete blade engagement, there is provided at each end of the longitudinal rib section 15 an integral laterally extended curved arm or section 20, so shaped as to completely fill the laterally extended end cut outs 12, thereby 35 further fixing the blade against side play and, additionally against end play. These curved arms or end sections 20 of the blade holding rib are laterally extended to ensure secure and accurate support for the blade throughout the entire 40 area of its bell-bar shaped opening. End sections 20 have crowns 21 curved both longitudinally and laterally, so that, when the blade is being positioned and strikes the curved crowns of the end sections, it will move easily and readily to its 45 final position. Preferably, the tops of the 50

crowned end sections 20 will be slightly below the peak or maximum height of the crown of the longitudinal section of rib 15 so that the blade will first contact the high point of the rib and then, as it swings and drops, will ride over the curved crowns of end sections 20. This construction permits the blade to move without any check or interference to its final position when it is dropped on the razor part, and a minimum of effort in centering and positioning the blade is secured. At their ends the sections 20 will be inclined downwardly, the tops of the inclines 21' being slightly curved, as shown in Figures 5 and 6 so as to permit an easy and sure dropping of the blade 10 to its final position.

The projections and recesses in the razor parts are so contoured as to fit closely together and to closely embrace the blade, in order to eliminate any interspaces. This gives a liquid sealed relation of the parts and prevents collection of water between them. This feature is of very considerable value from a practical standpoint. A precision made blade holder with the parts closely fitted, as shown, provides a construction in which the objectionable retention of liquid is eliminated and need of separating the parts and the blade for removing liquid deposits is done away with.

The blade, patterned as herein disclosed, ensures, when flexed, a uniform bending of the blade throughout its entire area, eliminating to a marked degree diverse strains and stresses in the blade such as result with blades having complicated cut outs, and gives evenly stressed cutting edges. The blade-receiving razor part shown and described, lends itself to the easy and ready seating of the blade in its final position, without the necessity of particular and careful manipulation of the blade to bring the parts together, and, when finally assembled, the blade is securely fixed in proper relation to the razor parts.

The disclosure here made is of particular, operative, and satisfactory construction. It is obvious that mechanical changes without departing from the inventive concept and principle, may

be made. All such changes which fall within the range of the appended claim are to be regarded as within the purview of the invention.

I claim:

5 A safety razor having a blade holder including a guard member, a co-acting cap member, said guard member having a centrally disposed recess, said cap member having an integral longitudinally disposed central rib arranged to fit into said recess when the parts are assembled, said longitudinal rib having straight sides and terminating in transverse arms extending laterally from the end thereof, said transverse arms having curved sides concentric with the center of said longitudinal rib, said rib and arms having crowned tops curved longitudinally and laterally to facilitate insertion of the blade in proper position on the holder between said members, the crown of the longitudinal rib projecting outwardly a greater distance than the crowns of the lateral arms so that the blade initially engages the longitudinal rib and then the lateral arms in order to be accurately and precisely positioned between the members when the parts are assembled, and means for clamping the blade between said members to insure a liquid excluding contact.

JOHN W. CLARK.
